UNITED STATES PATENT OFFICE.

JOSEPH E. TURNER, OF MANITOU, COLORADO.

RADIO STATIC-ELIMINATING APPARATUS.

Application filed January 10, 1927. Serial No. 160,143.

My invention relates to radio static eliminating apparatus.

The object of my invention is to provide a novel apparatus for conducting static received with radio signals to ground before the static reaches a receiving set, while permitting radio signals to enter the set.

My invention provides further novel static eliminating means of the kind described, having means for connection to ground, to an aerial conductor and to the intake terminal of a receiving set.

The novel features of my invention are hereinafter fully described and claimed.

15 In the accompanying drawing, which illustrates the preferred embodiment of my invention.

Fig. 1 is a central vertical section of my improved static eliminating device.

20 Fig. 2 is a cross section on line 2—2 of Fig. 1.

Fig. 3 is a diagrammatic view of an electric circuit which includes the conductive portions of my improved eliminating device.

25 Similar reference characters designate similar parts in the different views.

My improved static eliminating device includes a container 1, which, for example, may be cylindrical and have a height of six 30 inches and a diameter of four inches, and which may be provided at its upper end with a cover 2, having mounted therein three terminals 3, 4 and 5, which are insulated from each other.

35 The terminal 3 is adapted to be connected to an aerial wire 6. The terminal 5 is adapted to be connected by a wire 7 to the intake terminal 8 of a receiving set, Fig. 3.

The receiving set has the usual terminal 40 9 connected by a wire 10 to ground.

A U-shaped conductor 11 in the container 1 has its ends respectively connected to the terminals 3 and 5.

45 A wire 12 connects the terminal 4 to ground independently of the grounding of the set by the wire 10.

For diverting the static received with the signals, conductive means having relatively large area is provided in the container 1, and may consist in a vertical conductive plate 13 having connected to its lower corner portions respectively two portions 14 of the conductor 11, the plate 13 being, preferably, disposed between the arms of the conductor 11.

55 A wire 15 connects the plate 13 with the terminal 4. Said wire 15 may have branches

15' interwoven through holes 16 in the plate, as shown, to assure a good connection between the plate 13 and wire 15.

The conductor 11 may be disposed in a 60 tube 17, which may be soft rubber, the ends of the tube being closed by plugs 18. The portions 14 of the conductor 11 extend through holes provided in the tube 17.

To retain the plate 13, tube 17 and conductor 11 firmly in place in the container, the latter may be filled to the tops of the plugs 18 with packing material, 19, which may be conductive material, such as charcoal, or which may be non-conductive material, such as asbestos fiber. If charcoal is used, it may have mixed with it a small amount of salt and muriatic acid in solution. Plaster of Paris 20 covers the material 19.

The salt and acid serve to make a good 75 electrical connection between the charcoal and the plate 13, whereby the charcoal assists the plate 13 to collect and divert the static, which to a large extent is carried to ground through the wires 15 and 12 and 80 terminal 4, the amount of static passing to the set being insufficient to interfere with the clearness of the radio signals received by the set through the conductor 11, terminals 3 and 5 and wire 7. The volume of 85 such radio signals, with good reception and a good set, is of sufficient strength to afford good audibility, and the signals are very clear.

Any good receiving set may be employed, 90 which has a usual tuning element, such as a tuning coil 21. One terminal of the coil 21 is connected to the intake terminal 8, Fig. 3. The grid 22 of a detector tube 35 is connected to a conductor 23 which has a 95 contact 24 slidably engaging, in the usual manner, the windings of the coil 21. The plate 25 of the detector tube 35 is connected by a conductor 26 with one terminal of a head set 27, the other terminal of which is connected by a conductor 28 to the positive pole of a B battery 29. The negative terminal of the battery 29 is connected by a conductor 30 with one terminal of the filament 31 of the detector tube 35. The other terminal of the filament 31 is connected to the positive pole of an A battery 32 by a conductor 33. The negative pole of the battery 32 is connected by a conductor 34 to the conductor 30.

100 In the use of the invention, the separate ground connection, for the plate 13 is essen-

tial in the proper functioning of the device, and the set should be connected to a good aerial, to offset the loss of such radio signals as seek the ground through the wire 5 12, instead of entering the set.

The metal container 1 may be insulated from the charcoal 19 by an insulating coating of any suitable material, such as enamel, or it may be coated with pitch to keep 10 the acid and salt from attacking the metal, or the container itself may be of insulating material, such as hard rubber. Aside, however, from the chemical action which may take place and deteriorate the container, if 15 of metal, it is not necessary to insulate the container, as, like the charcoal and plate 13, it serves, when in electric connection with the plate 13, through the charcoal 19, to assist the plate 13 in diverting, collecting 20 and carrying off static.

The plate 13 may be of any good conductive material, such as copper, silver, or aluminum. It should have relatively large area, as shown, and may be flat, as shown, 25 or any other desired configuration.

With the use of my invention, I have had wonderfully clear reception at times and under conditions which made the signals given out by the set unintelligible, when 30 the eliminating device described was not used in connection with the set.

I do not limit my invention to the specific features of construction shown and described, as many modifications, within the 35 scope of the appended claims, may be made

without departing from the spirit of my invention.

What I claim is:—

1. In a radio static eliminating apparatus, a container having three insulated terminals, two of which are adapted to be respectively connected to an aerial conductor and to the intake terminal of a receiving set, a conductor in said container connecting said two insulated terminals, the third of said terminals being adapted to be connected with ground, static collecting means of relative larger area and capacity in said container connected to said third terminal and to said connecting conductor, and conductive packing material in said container in which said collecting means is embedded. 40

2. In a radio static eliminating apparatus, a container having three terminals insulated from each other, two of which are adapted to be respectively connected to an aerial conductor and to the intake terminal of a receiving set, the third terminal being adapted to be connected to ground, a conductor in said container having its arms respectively connected to said two terminals, a conductive plate of relatively large area disposed between and connected to the arms of said conductor and connected to said third insulated terminal, and conductive 45 packing material in said container in which said plate is embedded. 50

In testimony whereof I have signed my name to this specification.

JOSEPH E. TURNER.
